EXAMINING TABLE

Charles W. McClure, Boston, Mass., and Ludwig
Streifeneder, Chicago, Ill.

Application August 9, 1950, Serial No. 11,684

Term of patent 14 years

(Cl. D83—1)

To all whom it may concern:

Be it known that we, Charles W. McClure and Ludwig Streifeneder, residing respectively at Boston, Suffolk County, Massachusetts, and at Chicago, Cook County, Illinois, have invented a new, original, and ornamental Design for an Examining Table, of which the following is a specification, reference being had to the accompanying drawing, forming a part hereof.

Figure 1 is a perspective view of an examining table showing our new design.

Figure 2 is another perspective view thereof as it appears in adjusted position with the parts shown in dotted lines in Fig. 1 removed therefrom.

The characteristic features of our design reside in the portions shown in full lines in the drawing.

We claim:

The ornamental design for an examining table, as shown, and described.

CHARLES W. MCCLURE.
LUDWIG STREIFENEDER.
